PROCESS AND APPARATUS FOR PRODUC-
ING SEAMLESS CELLULOSE TUBESWaldemar Schwalbe and Otto Schnecko, Wies-
baden-Biebrich, Germany, assignors to The
Visking Corporation, Chicago, Ill., a corpora-
tion of VirginiaApplication December 5, 1933, Serial No. 701,010
In Germany December 22, 1932

4 Claims. (Cl. 18—15)

The present invention relates to the manufacture of seamless cellulose tubes, produced, for example, from viscose solutions.

The primary object is to provide an improved process of manufacture which involves maintaining the tube in inflated condition during substantially all of the period of time while the viscose is undergoing regeneration, that is, being converted to cellulose.

10 The viscose solution may be extruded through an annular nozzle upwardly through a coagulating and regenerating bath in a known manner. The present invention contemplates, however, the carrying of the tube in inflated condition, not only through the extrusion bath but also through subsequent baths until the regeneration is complete. Thereafter, the tubing may be wound in flattened condition upon a take-up roll, preferably after having been purified by suitable washings; or it may be conducted, still in an inflated condition, through suitable drying apparatus.

In accordance with the invention as preferably practiced, gases generated within the tube which is being drawn are permitted to escape rearwardly through a drainpipe which extends downwardly through the inner extrusion-member of the extruding-device, this drain-pipe serving also to permit escape of overflow from the internal bath.

The invention may be practiced by means of any preferred apparatus. The accompanying drawing illustrates diagrammatically apparatus which may be used in the practice of the process. In the drawing:—

Fig. 1 is a broken vertical sectional view of apparatus adapted to practice of the process; Fig. 2, an enlarged broken vertical section of the lower part of the extrusion-tank and the extrusion-device connected therewith; and Fig. 3, an elevational view of one of a series of drums which serve to carry the extruded tubing through a series of baths.

Referring to the drawing, A designates an extrusion-tank which contains an external bath, indicated at 1, this bath preferably consisting of a solution of a suitable coagulating compound and a suitable regenerating compound; B, an extrusion-device mounted in the tank and extending through the bottom thereof, said extrusion-device having associated therewith a tubular mandrel B' having a base-portion B² fitted with a plug B³ from which depends a drain-pipe B⁴ which extends downwardly through the inner member of the extrusion-device and

is equipped at its lower end with a trap B⁵; C, an admission-pipe through which the external bath is admitted to the lower portion of the tank; D, a viscose-admission pipe which leads to the space between the inner and outer extrusion-members of the device B, in a known manner; E, an admission-pipe through which a suitable coagulating and regenerating fluid is admitted to the space between the drain-pipe and the inner member of the extrusion-device, so that this internal bath may be delivered into the space between the mandrel and the viscose tube; F, a viscose tube which issues from the annular extrusion-orifice of the device B and passes in inflated condition through the several baths; G, a series of regenerating baths in which the final stages of regeneration may be completed; H, a bath in which the cellulose tube may be washed; I, a bath through which the purified tube may be passed, this bath containing, if desired, a small percentage of glycerine; J, a take-up roll upon which the tubing is wound in flat condition; K, a series of drums upon which the tubing F is carried over and through the several baths; and M, M', guide-devices associated with the drums.

The tube F is shown as passing upwardly out of the tank A and about a grooved roller L from which it passes to the first drum. Preferably, the roller L and the drums are of large diameter and are suitably geared together and given a proper rate of rotation with relation to the desired speed of extrusion.

The guide-devices M and M' may be any suitable devices for causing the tube F to form a spiral on the drum as the tube is drawn onto the drum. In the form shown, each guide-device comprises a cross-bar 2 which supports a series of guide-fingers 3, which are suitably arranged and spaced to cause the tube to be wound, threadlike, upon the drum. The drums dip into the baths. If desired, they may be wholly immersed in the baths; or, if desired, regenerating fluid may be sprayed upon the tube F while it is being fed forwardly by the drums. Any suitable form of carriers which will serve to maintain the tubing in inflated conditions while it is undergoing regeneration may be substituted for the apparatus shown.

The drain-tube B⁴ has its upper end extending through the plug B³ and opening into the main portion B' of the mandrel. The position of the upper end of the mandrel determines the height of the internal bath which should cor-

respond approximately with the level of the outer bath.

The overflow from the outer bath is through an opening 4 into an external cup 4^a which is equipped with a drain-tube 4^b.

By reference to Fig. 2, it will be noted that the trap B⁵ is in the form of a cup which has threaded connection with the lower end of the drain-tube B⁴. The trap is provided with overflow openings 5 which are disposed above the lower end of the drain-pipe. Thus, the lower end of the drain-pipe may extend into the trapped solution, so as to maintain a desired moderate pressure within the tubing F. Any excess of gas above the gas required to maintain the desired moderate pressure is permitted to escape through the openings 5. In the beginning of the extrusion operation, after the tubing F has been led upwardly and forwardly for a certain distance, a moderate amount of air-pressure may be supplied to keep the tubing in distended condition until the action of the acid in the regenerating bath creates sufficient internal pressure to maintain the tubing in inflated condition.

The process described avoids injury to the tubing and permits escape of gases generated within the tubing undergoing regeneration; and by permitting gases to escape in this manner, it becomes unnecessary to resort to slitting of the tubing F from time to time to permit escape of gases. Thus, the improved process results in effecting a very considerable saving of tubing and serves to expedite the drawing process.

Where the tubing is wound in flat condition upon a take-up roll, the tubing may subsequently be conducted from the take-up roll through a suitable drying apparatus, and may be maintained in inflated condition during the drying operation. A method for maintaining an elongated body of air within the portion of the tubing undergoing drying is well known, and is not claimed herein.

In the early part of the extrusion operation, or at any other time, if necessary or desirable, air may be injected through the trap B⁵ into the viscose tubing.

It may be stated, with reference to the series of baths employed, that, any desired number of baths may be employed for any desired purpose.

It is quite common, for example, to use a series of baths which include a regenerating bath, a series of baths containing heated water, graduated in temperature, if desired, and a final bath containing a hygroscopic agent, such as glycerin.

The foregoing detailed description has been given for clearness of understanding only, and no unnecessary limitations should be understood therefrom, but the appended claims should be construed as broadly as permissible, in view of the prior art.

What we claim as new and desire to secure by Letters Patent is:

1. A process of producing seamless tubes from cellulose solutions, which comprises: extruding the solution in the form of a tube into a coagulating and regenerating bath and carrying the extruded tube, in inflated condition, through said bath and through a succession of baths, and permitting the gases generated within the extruded tube to escape rearwardly through the extrusion-device, whereby slitting of the tube at intervals is rendered unnecessary.

2. A process as set forth in claim 1, in which the extruded tube, after passing through a series of baths containing regenerating solution, passes through a purifying bath.

3. A process as stated in claim 1, in which the tube, after passing through the regenerating baths and a purifying bath, is subjected, while still in an inflated condition, to a drying operation.

4. Apparatus for forming cellulose tubes, which comprises: an extrusion-tank having fitted to its bottom an extrusion-device through which seamless tubing may be extruded upwardly into said tank; means for supplying coagulating and regenerating fluid as an external bath in said tank and as an internal bath within the tubing being extruded; vent-means in said extrusion-device for controlling internal gas pressure in said tubing; a series of additional treating tanks; and means for carrying the extruded tubing in inflated condition from the point of extrusion through the extrusion-bath and the succeeding baths.
